CANE

Glenn A. Henderson and William H. Winborne,
Los Angeles, Calif.

Application August 20, 1949, Serial No. 111,355

11 Claims. (Cl. 135—45)

1

This invention has to do with a cane or walking stick and it is a general object of the invention to provide a cane of improved, practical, construction and which possesses characteristics making it convenient, practical and desirable for use.

Canes or walking sticks are used for various purposes, as for example, by persons who are crippled, who are convalescing, as dress accessories, etc. Canes are commonly constructed of wood and to have the desired strength and rigidity the woods employed are usually heavy, and by their very nature are not always dependable, are subject to splitting, and they are subject to general deterioration. Further, in practice considerable difficulty is ordinarily experienced securing a handle to or on a cane body, and the ferrule at the lower end of the cane body commonly gives considerable trouble by working loose, or breaking off etc. Further, in practice the usual cane, for instance, a cane of wood, to be shortened requires a complicated operation removing the ferrule and refitting or reapplying the ferrule to the body following shortening of the body. In most cases the shortening of a cane requires the installation of a new ferrule and the ferrule of the cane is usually marred. These operations are rather cumbersome and time consuming and are not always satisfactory.

The present invention provides a cane construction involving an elongate tubular body of metal. The handle is fixed to the upper end of the body by being provided with an extension or shank fitting into the knurled upper end of the body and having fixed engagement therewith. The tip at the lower end of the body is preferably metal and is detachably secured to the body, preferably by means of a screw, and in the preferred construction a detachable cushion of rubber, or the like, is provided at the lower open end of the tip and when removed affords access to the screw by which the tip is secured to the body. Further, sound deadening means are provided and may involve a plug of deadening material such as wood, or the like, located in the body intermediate its ends, or filling or packing of granular material such as expanded vermiculite or both.

A general object of this invention is to provide a practical, simple, easily operated means for securing a tip to a cane body. In the preferred form of the invention the body of the cane is tubular and the tip is a simple elongate part with a shank entering the end of the body, the shank being expansible under the action of a screw so

2

that it can be set in engagement with the body to dependably remain thereon or therein until deliberately released.

5 A further object of this invention is to provide a cane wherein the handle is secured to a tubular metal body so that it is dependably and permanently joined thereto. With the construction provided by the present invention the handle is secured to the body against working loose, shifting or becoming detached and thus the cane can be relied upon for service over a long period of time.

10 Another object of this invention is to provide a cane with a tubular metal body with sound deadening means serving to take the ring or resonance out of the body so that it is without disagreeable tone of metal.

15 The various objects and features of our invention will be fully understood from the following 20 detailed description of typical preferred forms and applications of the invention, throughout which description reference is made to the accompanying drawings, in which:

25 Fig. 1 is a view of a cane embodying the present invention with certain parts broken away to show the features of construction. Fig. 2 is an enlarged detailed view of a portion of the structure shown in Fig. 1 being a view taken as indicated by line 2—2 on Fig. 1. Fig. 3 is a 30 transverse sectional view taken as indicated by line 3—3 on Fig. 2. Fig. 4 is an enlarged detailed section of a part of the structure shown on Fig. 1, being a view taken as indicated by line 4—4 on Fig. 1. Fig. 5 is a transverse sectional view, 35 being a view taken as indicated by line 5—5 on Fig. 4, and Fig. 6 is a view illustrating a cane embodying the present invention in an initial form and illustrating the manner in which it may be shortened. Fig. 7 is a view similar to the 40 upper portion of Fig. 6 showing a construction to be used between the body and handle. Fig. 8 is an enlarged detailed section taken as indicated by line 8—8 on Fig. 7. Fig. 9 is a view similar to Fig. 4 showing a construction that can be used 45 to connect the body and tip. Fig. 10 is a view similar to Fig. 9 showing a modification of the structure shown in Fig. 9. Fig. 11 is a transverse section taken as indicated by line 11—11 on Fig. 10, and Fig. 12 is a transverse section taken as indicated by line 12—12 on Fig. 10.

50 The cane embodying the present invention involves, generally, a body A, a handle B, mounting means C securing the handle to the upper end of the body, a tip D preferably formed of metal, 55 mounting means E releasably securing the tip to

the lower end of the body, a cushioning means F on the tip and sound deadening means G in the body.

The body A, in accordance with the present invention, is an elongate tubular element preferably a single integral or continuous metal tube. In the form of the invention illustrated the tube forming the body A is round in cross section and in uniform in size or diameter throughout its length. In carrying out the invention it is preferred that the tube be thin walled and that it be formed of a light metal or a light alloy, the weight of the tubing, its size and the material being balanced so that the tube is as light as possible consistent with the desired strength and rigidity and durability.

The handle B may, in practice, be of any desired size, form or design, it being preferred that it be a unitary element shaped to provide an effective comfortable grip. It will be understood, of course, that the handle may be formed of a material or may be provided with a finish such as to gain the desired appearance or to be suitable with the body A which may, of course, be surfaced or finished in any desired manner.

The mounting means C provided for securing the handle to the upper end of the body A rigidly and permanently secures the handle to the body. In accordance with the invention the means C involves a shank or projection 10 on the handle engaged in the upper end of body A. The shank 10 is preferably an integral extension or continuation of the handle and in the case illustrated it is round in cross section and of such size as to fit tightly in the body. As shown in the drawings the shank 10 may be reduced somewhat relative to the stem portion 11 of the handle so that a shoulder 12 is formed to abut the end 13 of the handle and so that the exterior of the stem portion 11 of the handle is flush with the exterior of body A. In accordance with the present invention knurling is provided on the inner surface of the body wall at the upper end portion of the body. The knurling may be formed or provided by applying a suitable tool or implement to the material of the body A to establish the desired projections or knurling thereon. The inner surface of the body wall at the upper end portion of the body is roughened or knurled for a distance sufficient to have knurling engage the shank 10 throughout its length. In accordance with the invention the shank 10 projecting from the handle meshes with the knurling on the inner surface of the body wall so that the shank is anchored in the body against rotation therein or removal therefrom. In practice the desired meshing of the shank 10 with the knurling may be gained as the handle is applied to the body by temporarily softening the material of the shank 10 either by heat or by a suitable softening agent or solvent. In practice it is desirable to form the handle B and the shank 10 which projects therefrom as a unitary body of material popularly known as plastic, employing a so-called plastic which is subject to being softened by a suitable solvent such as an acetate, or the like. This type of plastic is preferred in that it may be obtained having the desired strength, is generally pleasing in appearance, and is generally practical for the formation of the handle.

The tip D is preferably a metal part that projects from the lower end of the body and, in practice, it may vary widely in form, proportioning or design. In the case illustrated the tip is of substantial length and is tapered down-

wardly so that it is considerably smaller at its lower end than where it joins the body A. In the case illustrated the upper end 14 of the tip abuts the lower end 15 of the body A and at the point of engagement of the tip with the body the tip and body are of the same size, or diameter.

The cushion F is carried by the tip D at its lower end and projects downwardly therefrom. It is preferred that the cushion be a body or button of rubber or rubber-like material, and it may have a concave or round ground engaging surface 20. The construction or means provided for securing the button-like cushion to the tip D preferably involves a lug or projection 21 which is an integral part of the cushion, which lug fits snugly or tightly into a socket 22 entering the tip D from its lower end. The upper end of the lug 21 seats on or against the bottom 23 of the socket and the parts are preferably proportioned so that when the lug 21 is seated on the bottom 23 of the socket and the parts are preferably proportioned so that when the lug 21 is seated on the bottom 23 of the socket, face 25 of the cushion is at or close to the end 26 of the tip D but does not necessarily bear thereon with pressure such as might result in cutting of the cushion where the lug joins the cushion.

The mounting means E releasably secures the tip to the body and in the preferred form of the invention it involves a shank 30 on the tip D fitting into the lower end of the body and an expander 31 acting on or with the shank 30 to expand it into gripping engagement with the body A. The shank 30 is preferably an integral extension or continuation of the tip D and where the body A is round tubing, as hereinabove described, the shank is round or turned and is of such size as to fit snugly into the lower end portion of the tubing forming the body and is preferably long enough to provide ample bearing in the body so that the tip is effectively supported in alignment with the body. The shank may have a sliding fit in the body 10 so that it can be easily arranged in or removed from the body.

The shank 30 of means E is expansible so that it can be operated into gripping engagement with the body A. In the preferred form of the invention the shank 30 is split longitudinally and in the drawings it is shown as having a single central or diametrically disposed cut or slit at 33, which slit extends a substantial distance lengthwise or into the shank 30 from its upper end. The expander 31 is preferably a screw suitably engaged with the shank 30.

In the form of the invention illustrated the unit formed by the tip D and the shank 30 of means E is provided with a central longitudinal opening 40 that extends from the lower end portion of the tip D to the upper end of the shank 30. The opening 40 in the case illustrated extends from the bottom of socket 22 to the split upper end portion of the shank and the portion 41 of the opening within the slit portion of the shank is reduced in diameter and is threaded. At the lower end of the reduced portion 41 there is a downwardly facing tapered or inclined shoulder 42.

The expanding member or screw 31 has a threaded body 44 that threads into the reduced opening 41 and it has a head 45 which is provided with a tapered face 46 abutting the shoulder 42. A screw driver slot 46, or the like, provided on the head 44, faces downwardly or is accessible through the opening 40 so the screw can be conveniently operated by a tool such as a screw driver

introduced through the opening 40 when the rubber, or rubber-like, cushion is removed from the tip. With the construction just described tightening of the screw in the opening 41 causes the head of the screw to wedge in the expandable portion of the shank spreading the shank into gripping or pressure engagement with the body A. In the preferred form of the invention the shank 30 is reduced in diameter at 59 for a suitable distance intermediate its ends, forming a neck portion 51 which is thin walled and therefore somewhat flexible, leaving the shank with a lower bearing part 52 that engages in the body A and an upper bearing part 53 that engages in the body A. Through this construction, which is illustrated in Fig. 4 of the drawings, the split portion of the shank is readily expandable under the action of the screw, and when the screw is tightened the upper bearing part 53 is effectively forced into pressure engagement with the body.

The sound dampening or deadening means G employed in the construction acts to prevent the other parts of the cane, and particularly the body A, from ringing or vibrating so that it has a metallic sound. The means G, as shown in the drawings, may involve two mediums or elements in the body A, for example it may involve a plug 66 of deadening material in the body intermediate its ends and a filler or packing of granular material 61. In the case illustrated a filler or plug 60 of material such as wood is made tight in the body A intermediate the ends of the body and may alone be employed as the sound deadening means. The packing or filling of granular material 61 may be employed with or without a plug 60 and in practice it may be any suitable soft or sound deadening material. For example, expanded vermiculite may be employed to advantage and may be filled into the body A to completely occupy the body between the shanks 30 and 33 or to occupy the spaces left between the shanks and the plug 60. When vermiculite or the like is employed it may be loose or with a binder, in which case it is desirable that a stopper 65 of cotton, paper, or like material is applied after the granular sound deadening material has been inserted in the body from its lower end. A stopper 65 such as is shown in Fig. 1 will serve to retain the granular sound deadening material until the tip has been applied or while the tip is removed or being repaired or replaced.

With the construction provided by the present invention a person possessing a cane, or a merchant to fit a cane to a particular user, may readily take a long cane, such as is illustrated at X in Fig. 6, remove the tip D and then sever a portion 80 of the body, as shown at Y in Fig. 6, and he may then reapply the tip D to the cane, as shown at Z in Fig. 6, to provide a shortened cane.

The mounting means C shown in Figs. 7 and 8 connecting the handle B with the body A differs from that above described to the extent that the shank 10' on the handle, instead of being of uniform size or cross section from one end to the other leaving a shoulder 12 normal to the axis of the shank where the shank joins the handle, has a tapered portion 10^a which extends between the straight round portion and which fairs into the handle where the end of the body joins the handle. A small or limited fillet-like curved part 10^b may be provided where the part 10^a joins the handle and when this is the case the end portion of the body A which receives the shank is reamed

out or finished to have a tapered end portion 70 corresponding with the taper of part 10^a and it terminates at an edge 71 which may be slightly round to fit the fillet 10^b. This construction can be advantageously employed when the handle is formed of a plastic material, or the like, that may be weak where the handle joins the shank 10 if the structure is such as is shown in Fig. 1. In carrying out the form of construction shown in Fig. 7, the straight shank portion as well as the tapered shank portion 10^a may be externally knurled or only the straight shank portion may be knurled as illustrated in the drawings.

In Fig. 9 of the drawings the mounting means E' for securing the tip D to the body A has a plain straight shank portion 30', the exterior of which is finished to have slidable engagement in the body. This form of construction is suitable for use where the tip D and the shank 30' are formed of a so-called plastic, or the like, which material is softer than metal. In such case the expander or screw 31' has its head in wedging or expanding engagement with the tapered shoulder 42' and is threaded into a metal insert or nut 80 seated in a polygonal socket 81 provided in the inner end of shank 30'. With this construction the expander 31' can be tightened into the nut 80 to cause the portion of the shank between the head of the expander and the nut 80 to expand and thus be tight in the body A.

If the material out of which the tip with its shank 30' is formed is of a material that will not advantageously expand and grip the body, in the manner just described, the shank may be split longitudinally as at 33' in the manner illustrated in Figs. 10, 11 and 12 of the drawings.

In carrying out the invention as shown in Figs. 9 and 10, the opening 40' provided through the tip may be a straight uniform opening from the shoulder 42^a to the outer end 26' of the tip. In such case the cushion F may be of the type above described and may have a lug or projection 21 engaged in the opening 40'. In the case illustrated, and in order to provide a rest or support for the cushion and also to reinforce the tip, a plug 90 which may be formed of wood, or the like, is arranged in opening 40' so its end 23' forms a support for the projection 21 of the cushion.

Having described only typical preferred forms and applications of our invention, we do not wish to be limited or restricted to the specific details herein set forth, but wish to reserve to ourselves any variations or modifications that may appear to those skilled in the art and fall within the scope of the following claims:

Having described our invention, we claim:

1. A cane including, an elongate tubular body, a handle secured to the upper end of the body, a tip having an opening extending through it parallel with the body, means releasably securing the tip to the lower end of the body including an elongate expandable shank with a central longitudinal opening and projecting up from the top and engaged in the body, and a screw carried in said opening expanding the shank into gripping engagement with the body and accessible through the opening in the tip, and a detachable cushion at the lower end of the tip normally closing said opening.

2. A cane including, an elongate tubular body, a handle secured to the upper end of the body, a tip with a hole through it, means releasably securing the tip to the lower end of the body including an elongate expandable shank with a

central longitudinal opening projecting up from the top and engaged in the body, and a screw carried in said opening expanding the shank into gripping engagement with the body and accessible through the hole in the tip, and a detachable cushion at the lower end of the tip normally closing said opening, the cushion having a rubber lug frictionally engaged in the hole in the tip.

3. A cane including, an elongate tubular body, a handle secured to the upper end of the body, a tip with a passage through it, and means releasably securing the tip to the lower end of the body including an elongate shank engageable in the body, the shank being split longitudinally from its upper end and having a central longitudinal opening through it from one end to the other and connecting with the passage in the tip, the opening having a reduced threaded portion where the shank is split, and a screw threaded in the reduced portion of said opening and operable to expand the shank and accessible through the passage in the tip.

4. A cane including, an elongate tubular body, a handle secured to the upper end of the body, a tip with a passage through it, and means releasably securing the tip to the lower end of the body including an elongate shank projecting up from the tip and engageable in the body, the shank being split longitudinally from its upper end and having a central longitudinal opening through it from one end to the other communicating with said passage, the opening having a reduced threaded portion where the shank is split establishing a downwardly facing inclined shoulder, and a screw threaded in the reduced portion of the said opening with a tapered head engaging said shoulder to expand the shank, the screw having a head at its lower end accessible for operation through the passage and the opening below the reduced portion.

5. A cane including, an elongate tubular body, a handle secured to the upper end of the body, a tip with a passage through it, and means releasably securing the tip to the lower end of the body including an elongate shank projecting up from the tip and engageable in the body, the shank being split longitudinally from its upper end and having a central longitudinal opening through it from one end to the other and communicating with the passage, the opening having a reduced threaded portion where the tip is split, and a screw threaded in the reduced portion of said opening and operable to expand the shank, the shank having a reduced portion where it is split forming a neck and a head at the upper end of the shank engageable with the body, the screw having a head at its lower end accessible through the passage and the opening below the screw.

6. A cane including, an elongate tubular metal body, two elements one secured to each end of the body and one detachable from the body, one element being a handle and the other a tip, and a sound deadener in the body including a packing of loose granular material in the body, substantially filling the body.

7. A cane including, an elongate tubular metal body, two elements one secured to each end of the body and one detachable from the body, one element being a handle and the other a ground engaging tip, and a sound deadener in the body including a wooden plug tight in the body intermediate its ends and loose granular sound deadening material in the body where it is not occupied by the plug.

8. A cane including, an elongate tubular metal body, two elements one secured to each end of the body and one detachable from the body, one element being a handle and the other a tip, and a sound deadener in the body including a packing of expanded vermiculite in the body.

9. A cane including, an elongate tubular metal body, two elements one secured to each end of the body and one detachable from the body, one element being a handle and the other a ground engaging tip, and a sound deadener in the body including a wooden plug tight in the body and expanded vermiculite in the body intermediate its ends and in sound deadening engagement with it.

10. A cane including, an elongate tubular body, a handle secured to the upper end of the body, a tip with a passage through it, and means releasably securing the tip to the lower end of the body including an elongate shank projecting up from the tip and engageable in the body, the shank being split longitudinally from its upper end and having a central elongate opening threaded where the shank is split, and a screw threaded in the opening and operating to expand the shank, the shank having a reduced portion where it is split forming a neck and a head at the upper end of the shank engageable with the body, the screw having a head at its lower end accessible through the passage and the opening below the screw.

11. A cane including, an elongate tubular body, a handle secured to the upper end of the body, a tip with a hole through it, means releasably securing the tip to the lower end of the body including an elongate shank projecting up from the tip and engageable in the body, the shank being split longitudinally from its upper end and having a central longitudinal opening through it from one end to the other and communicating with the hole, the opening having a reduced threaded portion where the shank is split, and a screw threaded in the reduced portion of said opening and having a head at its lower end operable to expand the shank, the shank having a reduced portion where it is split forming a neck and a head at the upper end of the shank engageable with the body, and a detachable cushion at the lower end of the tip normally closing said opening and having a part frictionally held in the hole in the tip.

12. A cane including, an elongate tubular body, a handle secured to the upper end of the body, a tip with a hole through it, means releasably securing the tip to the lower end of the body including an elongate shank projecting up from the tip and engageable in the body, the shank being split longitudinally from its upper end and having a central longitudinal opening through it from one end to the other and communicating with the hole, the opening having a reduced threaded portion where the shank is split, and a screw threaded in the reduced portion of said opening and having a head at its lower end operable to expand the shank, the shank having a reduced portion where it is split forming a neck and a head at the upper end of the shank engageable with the body, and a detachable cushion at the lower end of the tip normally closing said opening and having a part frictionally held in the hole in the tip.
